CLAIM

The ornamental design for a bottle, substantially as shown and described.

DESCRIPTION

FIG. 1 is an elevational view of a bottle showing our new design;

FIG. 2 is a view looking from the right of FIG. 1;

FIG. 3 is a view looking from the left of FIG. 1;

FIG. 4 is a top plan view;

FIG. 5 is a bottom plan view;

FIG. 6 is a view showing the side opposite that seen in FIG. 1;

FIG. 7 is a fragmentary sectional view taken on the line 7—7 of FIG. 2;

FIG. 8 is a fragmentary sectional view taken on the line 8—8 of FIG. 1;

FIG. 9 is a fragmentary sectional view taken on the line 9—9 of FIG. 2.

FIG. 10 is a perspective view on a reduced scale;

FIG. 11 is an elevational view showing a modified form of our new design;

FIG. 12 is a view looking from the right of FIG. 11; and

FIG. 13 is a view showing the side opposite that seen in FIG. 11.

The left side, top and bottom views of the second embodiment are the same as the corresponding views of the first embodiment seen in FIGS. 3, 4 and 5.
